UNITED STATES PATENT OFFICE.

ANDREW STARK, OF CHICAGO, ILLINOIS.

GRAIN-HARVESTER.

SPECIFICATION forming part of Letters Patent No. 357,640, dated February 15, 1887.

Application filed November 3, 1884. Serial No. 147,143. (No model.)

To all whom it may concern.

Be it known that I, ANDREW STARK, a citizen of the United States, residing at Chicago, in the county of Cook and State of Illinois, 5 have invented certain new and useful Improvements in Grain-Harvesters, which are fully set forth in the annexed specification.

This invention relates to certain novel features and details of construction of the driving 10 mechanism of harvesting-machines, all of which are fully described, and set forth in the claims.

Figure 1 is a plan of the drive-wheel, main frame, and gearing. Fig. 2 is a front elevation of the same. Fig. 3 is a plan, Fig. 4 is an in- 15 side elevation, and Fig. 5 is a vertical section, of the main driving-pinion frame and the gearing bearing thereon. Fig. 6 is an outside elevation of the outside divider, grain-wheel, and bearings. Fig. 7 is a plan, and Fig. 8 is an 20 outside elevation, of the casting which secures the outside divider to the finger-bar. Fig. 9 is an outer elevation, and Fig. 10 is a plan, of the grain-wheel bearing piece.

A is the driving-wheel. A' is the driving- 25 gear thereon.

B is the main frame.

C is the main driving-pinion frame or bracket.

C' is the main driving-pinion.

30 D is the inner segment, which is secured to the cross-bar B² of the main frame. To the same inner segment, D, is secured the main driving-pinion frame or bracket C, which is also further secured at c to the cross-bar B² of 35 the main frame. The main driving-pinion C', which meshes with and is driven by the main driving-gear A', is fast on its own shaft C², which has its bearings in the main driving-pinion frame or bracket C. Said shaft is 40 clutched to the bevel gear-wheel G, which meshes with the bevel-pinion G', the shaft of which is journaled in the main driving-pinion frame C at right angles with the shaft C², and has at its rear end a crank, G², which drives 45 the sickle, and carries also, between the pinion G' and the crank G², the sprocket-wheel G³, from which power may be communicated to the conveying and binding mechanism. (Not illustrated.)

50 It will be noticed that the main frame B is made of a continuous iron, B' B'' B''', extending

from the finger-bar B⁴, to which it is attached at the point b, around the wheel to the rear sill, B⁴, to which it is joined at the rear outside corner, b⁴. I have so shaped this iron frame that the part B', from the finger-bar to the angle b', is in proper position and at a suitable angle to serve as the inside divider, thereby obviating the necessity for any additional device for that purpose. 55

M is the outside divider, its rear portion, M', being the end-board of the platform.

N is the grain-wheel bearing and guiding lever, and N' the grain-wheel.

P is a bracket, which serves the triple purpose of securing the outside divider to the finger-bar, affording secure attachment for the grain-wheel bearing and guiding lever, and being or having rigid with it the grain-wheel guide. This bracket P has the stubbleward 60 projection or lug p, to which the finger-bar is bolted. Integral with this lug is the last sickle-guard, t. The bracket P has also the projection or boss p' in line with the finger-bar, and bearing the pivot of the grain-wheel guiding-lever N. It has also the forward projection, p'', and the rearward projection, p''', to both of which the outside divider and end-board, M M', is secured. It has also extended rearward the segmental guide p² for the grain- 65 wheel, the additional guide-pulley or guide-stud p³ for the said platform supporting and adjusting cable W, the guide p³ being at the end of the finger-bar and in line therewith, so that it receives the cable W, which lies under 70 the finger-bar, and is guided to and retained in that position by the guide-pulley d on the lower end of the inner segment at the other end of the finger-bar. This arrangement of the finger-bar with relation to the segment and 75 the bracket P, with the guides placed as stated, causes all the strain upon said cable in sustaining the platform to be exerted upon the rigid finger-bar in the direction of its length, whereby is prevented any straining or wrenching of the platform or any connected parts of 80 the machine, since both guides—that on the segment and that on the bracket—are fixed on iron, which is bolted directly to the iron finger-bar which connects them, and in the direction of whose length the strain is applied. 85

The means for adjusting the frame and plat-

form herein illustrated and partly described are not designed to be claimed herein, but are made the subject of my application No. 102,762, filed August 4, 1883.

5 In order to render the segment on the inside of the wheel, to which all the driving-gearing is connected, the gear-frame being affixed directly to the segment, as above described, as rigid as possible, in addition to having it secured directly to the finger-bar B^5 , which is itself secured at two points to the main frame—viz., at b and b^5 —I extend from the upper end of the segment, grainward and downward to the inner side of the main frame, the upper frame-bar, B^3 , of three-eighth-inch iron, rigidly bolted both to the segment and to the main frame. This frame-bar serves as a support for any gearing which it may be necessary to mount upon the upper part of the machine to drive 20 either a binder or in some cases the reel.

The finger-bar, axle-guide, and main frame, each rigidly and directly secured to both the others, the general construction of the main frame comprising the iron frame-bar passing 25 around the front, outer side, and rear of the drive-wheel, and having the cross-bar inside the latter, and the inner segment secured to the cross-bar, and the finger-bar secured to both the segment and the main frame, I do not claim herein, because I have claimed such construction in my application No. 174,698, filed August 18, 1885, which was a division of my said former application No. 102,762, filed August 4, 1883.

35 I claim—

1. In a harvesting-machine, in combination with the platform and the finger-bar, the bracket P , adapted to be secured rigidly at the end of the finger-bar, and having integrally therewith the front and rear attachments for 40 the outside divider, the pivot for the grain-wheel guide-lever, and the segmental grain-wheel guide, substantially as set forth.

2. In a harvesting-machine, in combination 45 with the main frame, the cross-bar rigid therewith and extending from front to rear inside the drive-wheel, the inner segment rigidly secured to the cross-bar, the finger-bar rigidly secured to both the main frame and the lower 50 end of the inner segment, and the upper frame-bar secured rigidly to the upper end of the inner segment and to the inner side of the main frame, and thereby bracing the segment, substantially as set forth.

3. In a harvesting-machine, in combination 55 with the iron main frame secured rigidly to the finger-bar, and extending thence forward around the front, outside, and rear of the driving-wheel, and the cross-bar inside the driving-wheel rigidly secured front and rear to the main frame, and the inner segment secured to the cross-bar and to the finger-bar, the upper frame-bar secured rigidly to the upper end of the inner segment and to the inner side of the main frame.

4. In a harvesting-machine, in combination, substantially as hereinbefore set forth, the inner segment, the finger-bar, and the grain-wheel guide, the segment and the grain-wheel guide being both rigidly and directly secured 70 to the finger-bar.

5. In a harvesting-machine, in combination, the inside segment, the grain-wheel guide, and the finger-bar, the segment and grain-wheel guide being both secured directly and rigidly 75 to the finger-bar, and having, respectively, the inside and outside guides for the platform-supporting cable.

6. In a harvesting-machine, in combination, as set forth, the iron main frame secured to 80 the finger-bar, and extending thence forward around the front, outside, and rear of the driving-wheel, a cross-bar rigidly secured to the front and rear sides of the main frame inside the wheel, the inside segmental axle-guide rigidly 85 secured to the finger-bar and to the cross-bar, and the main driving-pinion frame rigidly secured to the segmental axle-guide and to the cross-bar.

7. In a grain-harvester, in combination with 90 the finger-bar and the outside divider, the bracket rigidly and directly secured to both and forming the connection between them, and having both the bearing and the guide for the grain-wheel guiding-lever, substantially as set 95 forth.

8. In a grain-harvester, in combination with the finger-bar, the bracket P , having integrally therewith the supports for the outside divider, and the outside finger or sickle guard, substantially as set forth.

In testimony whereof I have hereunto set my hand, in the presence of two witnesses, at Chicago, Illinois, this 2d day of July, A. D. 1884.

ANDREW STARK.
